CONE FOR DYEING YARN

Robert A. Russell, Alexander City, Ala., assignor to The Russell Manufacturing Company, Incorporated, a corporation of Alabama

Application September 27, 1952, Serial No. 311,839

1 Claim. (Cl. 68—198)

This invention relates to a cone for dyeing yarn, and more particularly to an improved cone of this type for use in the package dyeing of yarn and by which the dyed yarn packages are adapted for use directly in subsequent operations without any intermediate rewinding.

In my prior U. S. Patent No. 2,489,465, there is disclosed a cone of this general type having a perforated body permitting the passage of dye liquors therethrough, and having internal bushings at each end by which the cone is adapted to fit both a winder spindle adapter for placing a yarn package thereon and a dye machine spindle for disposition of the yarn package thereon for dyeing.

The embodiment illustrated and described in my above noted prior patent is adapted to be formed best of metal, although the possibility of using a plastic material is suggested and this has always been an attractive possibility because of the relative lightness over metal that might be obtained with plastic and because of the great flexibility in other physical properties, such as corrosion resistance, that are obtainable in plastic materials.

The difficulty with plastic materials, however, is that they provide appreciably less strength than metals, which is a very important consideration because of the substantial shrinkage stresses that are imposed on a carrier by a dyed yarn package, and further that they must be formed as a practical matter by a molding operation which substantially limits the shape that may be employed, as for internal bushings such as are disclosed in my above noted prior patent.

According to the present invention, there is now provided a cone for dyeing yarn of the type noted above that is formed of a molded plastic material and that obviates the difficulties just referred to. Briefly described, this plastic cone of the present invention is formed with perforations through the wall thereof to adapt it for package dyeing operations, with a central bore adapting it to fit on a package dyeing machine spindle and a winder spindle adapter, and with a solid wall from the central bore to the external cone surface, except for the perforations therein, by which an increasing wall thickness is provided toward the large end of said cone that affords increasing strength for withstanding the increasing shrinkage stresses imposed toward this large end by a dyed yarn package supported on the cone.

The increasing shrinkage stresses result from the increasing length of yarn wrap about the cone from the small end to its large end. This increase may, under usual circumstances, be of the order of about 20%, and the cone wall construction of the present invention allows this increasing stress load to be balanced nicely by increasing wall strength.

Another feature of the package dye cone of the present invention is that the wall construction provides a wall of substantial thickness so that the end faces when formed squarely allow face to face abutment with the end of an adjacent cone on a package dyeing machine spindle for substantial sealing of this joint against passage of dye liquor. This feature also provides a substantial area of

2

end contact between the cones when placed on a dye machine spindle thereby affording frictional resistance against any lateral shifting of the cones adjacent their large end due to clearance resulting from the fact that 5 the central cone bore is necessarily slightly tapered because of its molded form. The large end of the cone may alternatively be formed with a concentric recess in relation to the central bore for nesting over the small end of an adjacent cone and thereby positively positioning this 10 large end against shifting by reason of the tapered bore, as well as further sealing the joint between the cones, as will be noted more in detail presently.

These and other features of the plastic dye cone of the present invention are described in detail below in connection with the accompanying drawings, in which:

Fig. 1 is a quartered sectioned perspective view of a cone for dyeing yarn embodying the present invention;

Fig. 2 is a longitudinal section illustrating the manner in which the dye cone or yarn carrier shown in Fig. 1 may be stacked, as on a package dyeing machine spindle (not shown); and

Fig. 3 is a longitudinal section similar to Fig. 2, but showing the dye cones formed without the nesting recess in their large ends.

Referring now in detail to the drawings, the embodiment of the dye cone of the present invention illustrated in Fig. 1 is indicated generally by the reference numeral 10, and, as shown, comprises a tubular body member 12 of substantial wall thickness that is solid from a central bore 14 therein to an external conical surface 16 adapted for carrying a yarn package in the usual manner. When the wall of the body member 12 is said to be solid, exception is intended to be understood for a plurality of perforations 18 extending through the body member wall 20 to adapt the cone 10 for package dyeing operations. A nesting recess at the large end of the body member 12, such as has already been mentioned above, is also illustrated in Fig. 1 at 20.

The dye cone shown in Fig. 1 is formed according to 40 the present invention of a molded plastic material, as has already been noted above, the particular plastic material used being a matter of wide choice from among the many that are readily available, although a principal advantage of the use of a plastic material is the ease with which excellent corrosion resistance may be obtained and the selection should accordingly be made with this factor in mind. A representative example of a suitable plastic material for use according to the present invention that has exceptional corrosion resistant properties is Teflon, which is a tetrafluoroethylene Du Pont plastic.

Fig. 2 shows the manner in which the dye cones 10 may be stacked for arrangement on a package dyeing machine spindle (not shown) with the small end of each cone 10 nested in the recess 20 at the large end of the adjacent cone 10 so that an effective seal is formed at the joint 55 between the stacked cones 10 and dye liquor will accordingly be forced to pass through the cone perforations 18 and therefore through the supported yarn packages during the dyeing operation.

It should also be noted that this nesting arrangement 60 at the large end recess 20 provides positive means for positioning the dye cones 10 in relation to a dye machine spindle despite the molding taper that will necessarily be present in the central cone bore 14. This taper will ordinarily be slight, for it is required only to allow withdrawal of a bore forming mandrel during the molding operation, and accordingly no attempt has been made to represent it in the drawings, although it will be readily recognized from the drawings that this taper will increase the diameter of the bore 14 from the small end of the body member 12 toward the large end. The presence 65 of this taper has an actual advantage in adapting the bore

14 for disposition more readily over a dye machine spindle while employing a diameter at the top of the bore 14 that fits the spindle closely. This fact also makes it possible to position the large end of the tapered bore 14 through the recess 20 in relation to the closely fitting 5 small end of an adjacent dye cone 10 and thereby eliminate any effect of the taper as far as the stacked positioning of the dye cones 10 in relation to the dye machine spindle is concerned.

Alternatively, unless the taper required for the bore 14 is larger than usual, satisfactory sealing of the joint between the stacked dye cones and adequate positioning of them on a dye machine spindle may be obtained by forming the end faces of the cones squarely for face to face abutment with adjacent cones. This arrangement is illustrated in Fig. 3 of the drawing in which the dye cones are indicated generally by the reference numeral 10' and are shown formed of body members 12' having a central bore 14' and a conical external surface 16' with perforations 18' extending therethrough, all as previously described above except that no nesting recess is provided at the large end of the body member 12'. The substantial thickness of the wall of body members 12', however, provides a substantial area of contact between the abutting cone faces which will ordinarily seal the cone joint satisfactorily and provide sufficient frictional resistance to position the dye cones 10' at their large ends despite the taper required in the central bore 14'.

The present invention has been described above for purposes of illustration only and is not intended to be 30 limited by this description or otherwise except as defined in the appended claim.

I claim:

A yarn carrier for package dyeing of yarn comprising

a cone formed of a plastic material having corrosion resistant properties for withstanding attack by dye liquors, said cone having a plurality of perforations extending through the wall thereof for passage of dye liquors therethrough and having a central bore adapted to fit on a package dyeing machine spindle and a winder spindle adapter, said bore being tapered slightly and the wall of said cone being of substantial thickness, with the ends thereof formed entirely square for face to face abutment with the end of an adjacent cone on a dye machine spindle, and with said wall formed solid from said bore to the external cone surface, except for said perforations, and of increasing thickness from the small upper end to the large base end of said cone, the thickness of said base end being substantially twice the thickness of said upper end, whereby the increasing thickness of said wall toward the large end of said cone provides increasing strength for withstanding the increasing shrinkage stresses imposed toward said large end by a dyed yarn package supported on said cone and the substantial thickness of said wall provides for substantially sealed abutment at the ends of said cone with other adjacent cones when stacked on a dye machine spindle and for aligned positioning of said cones despite the taper of said bore.
